UNITED STATES PATENT OFFICE.

EDWARD P. CALDWELL, OF WATERLOO, IOWA.

COMPOUND RAIL.

1,073,213.

Specification of Letters Patent.

Patented Sept. 16, 1913.

Application filed October 1, 1912. Serial No. 723,336.

To all whom it may concern:

Be it known that I, EDWARD P. CALDWELL, a citizen of the United States, residing at Waterloo, in the county of Blackhawk and 5 State of Iowa, have invented new and useful Improvements in Compound Rails, of which the following is a specification.

This invention relates to railway rails, and more particularly to that type of rail 10 having a side groove and employed in the construction of street railways.

It is the object of this invention to provide a compound rail in which novel means is provided for the removal of one of the 15 sections for the purpose of renewal when such section becomes worn.

Referring to the drawings:—Figure 1 is a sectional view of the complete rail assembled as in use, and showing the road bed construction used in connection therewith; and, Fig. 2 is a side elevation partly in section of a section of the track as constructed with my new rail.

Referring more particularly to the drawings, the numeral 1 designates the head of the rail which head is provided with an integral depending web portion 2, which is provided with suitable bolt apertures 2¹.

The base of the rail comprises two angle bars 3 and 4 provided with bolt apertures 3¹ and 4¹ and each of which is cut away as at 5 to form a shoulder 6, these angle bars 3 and 4 when secured together forming a pocket to receive the depending web portion 2 of the head 1. The angle bar 3 is provided with an upwardly extending portion 7 which projects up around the side of the head of the rail as shown at 8, and forms a brace therefor as against any 40 lateral strain which may occur in the passing of a train thereover. The vertical portion 9 of the angle bar 4 is curved outwardly at 10 and upwardly at 11 which latter portion is spaced from the head 1 of 45 the rail to form an intermediate groove 12 within which the flange of the wheel travels. This angle bar 4 also extends upwardly under the head of the rail, and at the base 50 of the groove 12 it is provided with an integral extension 13 which surrounds the head 1 in a manner similar to the portion 8 of the member 3.

The two angle bars 3 and 4 are permanently secured together by means of 55 rivets 14, and the base thus formed rests upon the tie plate 15 which in turn is sup-

ported upon the tie 16. The ordinary spikes 17 are employed to secure the base and tie plate in place on the tie 16.

In constructing the roadbed, the tie, tie 60 plates, spikes and base are partially embedded in concrete or the like as shown in Fig. 1, the upper extremity of the base being above the level thereof and leaving the pocket free for the reception of the depending portion 2 of the head 1. The depending portion 2 of the head 1 is inserted in the pocket formed by the wall 5 and 6 of the angle bars 3 and 4, and held therein by bolts 20 which pass through the bolt apertures 3¹ and 4¹ of the angle bars 3 and 4 and the bolt apertures 2¹ of the depending portion 2 of the head 1. A nut 21 is employed to secure the bolt in place.

By this construction it will be seen that 75 I have devised a rail in which the head thereof may be readily removed and replaced when it has become worn and useless, without disturbing the roadway construction, thus obviating the necessity of excavating 80 streets when it is desired to renew a rail.

What is claimed is:—

1. A compound rail embodying a head; an integral extension depending therefrom, a base comprising two members each having 85 its upper extremity cut away to form a pocket for the reception of said depending integral extension, the upper extremity of one of the base members embracing the side of the rail head, and the upper extremity 90 of the other of the base members having its upper extremity bent and spaced from said head to form an intervening groove, and means for securing the base sections and the rail head together.

2. A compound rail embodying a rail head, an integral web depending therefrom, a base comprising two members, means for securing the depending integral web between the base members, one of the base 100 members extending upwardly and engaging the side face of the rail head, the other base member being bent upwardly and outwardly to form a groove between its upper extremity and the rail head, and means integral with the last mentioned base member at the base of said groove for engaging the side face of the rail head.

3. A compound rail embodying a rail head having an integral depending web, a 110 base comprising two angle members, one of said base members having its upper ex-

- 5 tremity tapered and embracing the outer face of the rail head, the other base member being of greater height than the first mentioned base member and having its upper extremity bent outwardly to form a groove between itself and the inner face of the rail, means integral with the last mentioned base member at the base of the groove for engaging the inner face of the 10 rail head, means for securing the base members together, and means for securing the depending web between the base members.
- 15 4. A compound rail embodying a rail head, an integral web portion depending therefrom, two right angle base members each having a cut away portion to receive the integral depending web portion, means for securing the base members together, means for securing the depending web portion between the base members, and means for engaging the side faces of the rail head, said means comprising the tapered upper 20 extremity of the base members.
- 25 5. A compound rail embodying a head, an integral extension depending therefrom, a base comprising two members each having its upper extremity cut away to form a pocket for the reception of said depending integral extension, the upper extremity of 30 one of the base members embracing the side of the rail head, and the upper extremity of the other of the base members having its upper extremity bent and spaced to form an intervening groove, means for securing

the base sections and the rail head together, 35 and an integral extension on the last mentioned base member near its extremity for engaging the side face of the rail head.

6. A compound rail embodying a rail head, an integral depending web portion, a 40 plurality of right angle base members each having a cut away portion adapted to receive the integral depending web portion, one of the base members having a tapered upper extremity engaging one of the side 45 faces of the rail head, the other base member having its upper extremity bent outwardly and spaced from said rail head to form an intervening groove, means for securing the base members together, and 50 means for securing the depending web portion between the base members.

7. A compound rail embodying a rail head, a plurality of right angle base members having vertically extending portions 55 of different lengths, the vertical extending portion of greatest length being bent to space it from the rail head to form an intervening groove, and means for securing the base members and rail head together. 60

In testimony whereof I have hereunto set my hand in presence of two subscribing witnesses.

EDWARD P. CALDWELL.
